[57] CLAIM

The ornamental design for a shoe, as shown.

DESCRIPTION

FIG. 1 is a right side elevational view of a shoe showing my new design;

FIG. 2 is a top plan view thereof;

FIG. 3 is a bottom plan view thereof; the wavy line pattern being understood to be continuous;

FIG. 4 is a left side elevational view thereof;

FIG. 5 is a rear elevational view thereof;

FIG. 6 is a front elevational view thereof.

*Fig. 1**Fig. 2**Fig. 3**Fig. 4**Fig. 5**Fig. 6*
